UNITED STATES PATENT OFFICE

GERRIT SCHOTEL, OF THE HAGUE, NETHERLANDS

THERMIONIC TRANSMITTER AND RECEIVER

Application filed September 20, 1926, Serial No. 136,652, and in the Netherlands September 25, 1925.

The invention relates to improvements in or relating to thermionic transmitters and receivers more particularly for short waves.

The improvements according to the present invention with regard to the thermionic transmitters more particularly for short waves consist in that two or more circuits are coupled very tightly with each other, e. g., by means of a common coil with tapping 10 points and are inserted in the circuit of a discharge tube and by suitable means the higher or one of the higher resonant frequencies is brought into action. Hereby the efficiency may be regulated by alteration of 15 the winding-ratio of the coupling coil or coupling coils. With the aid of an adjustable coil connected to the regulating electrode, which forms with the capacity of the tube an oscillating circuit, the invention includes the regulating of this circuit to a frequency which is higher than the operating 20 frequency.

With regard to thermionic receivers the invention consists in the improvement where- 25 by two or more circuits tightly coupled with each other are inserted in the grid circuit of a discharge tube and the circuits so ad- justed that the higher or one of the higher resonant oscillation frequencies is the same 30 as the wave-length to be received, or approxi- mately so in case of beat reception. Hereby the efficiency of reception can, when nec- essary under application of known means for re-tuning be regulated by alteration of 35 the winding-ratio of the coupling coil or of the coupling coils.

Other characteristics of the invention are that in the case of a transmitter the self- 40 induction of the coupling coil or of the cou- pling coils between the tube and the antenna is many times larger than the self-induction of the coil in the regulating, or grid circuit.

The invention is explained hereafter and is illustrated in the accompanying drawings, 45 in which—

Figure 1 is a diagram of connections when using the method according to the invention for transmitting purposes;

Figure 2 is a modification in the connec- 50 tions of Figure 1;

Figure 3 shows a diagram of connections in which the aerial has been replaced by an adjustable condenser and a resistance;

Figure 4 is a diagrammatic representation explaining the conditions of operation of the 55 electron tube;

Figure 5 shows the connections for using the present invention for receiving purposes;

Figure 6 shows the connections for ampli- 60 fying purposes; and

Figure 7 is a diagram of a push-pull cir- 65

Referring to Figure 1, the electron tube 1 has a filament 2, a grid 3 and an anode 4. The tube anode circuit may be fed in parallel, as illustrated. However, this method of feed- 70 ing anode current to the tube is optional, and any other usual method may be used if de- sired. With a parallel feed, the blocking condenser 5 is provided for preventing the direct current of the anode battery or genera- 75 tor from taking the wrong path through the coil 6. The latter has two adjustable tapping points, one of which is used for the anode cir- circuit 7 and the other for the aerial 8.

The grid circuit comprises an adjustable self-induction coil 9 connected in series with a grid resistance 10 bridged by a condenser 11. The capacity present in the electron tube provides a coupling between the anode cir- 80

85

uit and the grid circuit, whereby according to a known principle electric oscillations are continuously produced in the said circuits. By suitably selecting the elements arranged in Figure 1 between the grid and the filament in a manner to be more fully described the electron tube will oscillate with a consider- 90

95

system consisting of the coupled circuits 2—3—4—5—6 and 6—8—aerial—earth is reso- nant to two frequencies differing considerably from one another owing to their very tight coupling. Out of these frequencies it is pos- sible for example to select the highest (apart from the action of the coupling with the grid circuit whereby strictly speaking there is the possibility of more than two frequencies with the present connections) by selecting the ele-

ments of the grid circuit so that the internal capacity coupling of the electron tube produces a grid tension having the correct phase and amplitude, with the result that the oscillations of the highest frequency (or if necessary the intermediate frequency, in the case of more than two possible frequencies) may continue. In the case of Figure 1 the correct phase above mentioned is attained by selecting the inductance of the coil 9 so as to make the natural frequency of the circuit consisting of this coil and the tube capacity slightly higher than the frequency of the oscillations generated. Any tendency to oscillate at a frequency considerably lower than that to which the grid circuit is tuned will not be sustained by the action of the grid-filament circuit because the low inductance of the coil 9 will form a short circuit for the lower frequency. Figure 1 is of course given as an example, since a number of modifications may be made in the connections without departing from the fundamental principle of the invention.

Referring to Figure 4, illustrating a diagram with two circuits coupled to one another, the operation of the tube is as follows, knowing that C_1 is the internal tube capacity between anode and filament terminals of the electron tube; the influence of the grid coil being also taken into account; L the inductance at no load of a transformer without losses and magnetic leakage, that is to say having a 100% efficiency; l an inductance; C a capacity; and R a resistance. The value of the last two elements is given when they represent the electric values of the aerial.

It must be understood that the following explanation is only of an approximate nature for the reason that the two circuits coupled to one another in the anode circuit are likewise coupled to the grid circuit over the interior of the electron tube so that, as previously stated, this is not a two-circuit system, but one constituted of three circuits. Generally however the coupling of the grid circuit with the other circuits is, if the adjustments are right, loose, so that the larger natural frequencies are not far apart.

Figure 4 is a diagrammatic representation of the connections of Figure 1. The block condenser 5 is omitted and the ratio of transformation u (i.e. the turn ratio from primary to secondary) of the transformer 6 is assumed to be $u=1:1$. This transformer is therefore replaced by an inductance L representing the no-load inductance.

As a rule L is many times greater than l and C many times greater than C_1 . The resonant frequencies of the system are approximately:

$$F_1 = \frac{1}{2\pi\sqrt{LC}} \quad F_2 = \frac{1}{2\pi\sqrt{lC}}$$

Should the winding ratio of the transformer be u instead of unity, then l and R are

first to be multiplied by u^2 and C to be divided thereby.

In the present invention frequency F_1 is used, care being taken that F_2 is kept in check.

The transformer may be omitted when the winding ratio is $u=1$. This extreme case is shown in Figure 2, in which the aerial is directly connected to the coil 12.

Figure 3 illustrates the general case, in which the winding ratio u of the transformer varies from unity, and there is a certain amount of magnetic leakage which will appear as self-induction in the circuit from which the energy is available.

The capacity of the aerial is replaced in this case by a variable condenser 13. Also a variable self-induction may be connected in place of the aerial, or the transformer may be short-circuited (extreme case of the condenser connection with infinite capacity according to Figure 3).

The wave-length may be altered firstly by altering the winding ratio of the transformer, this being done in practice by displacing one or both contacts.

Assuming the transformer has no leakage nor losses and no distributed capacity, we have in case $C >> u^2 C_1$ the frequency:

$$F_1 = \frac{1}{2\pi\sqrt{u^2 l C_1}} = \frac{1}{2\pi u \sqrt{l C_1}}$$

which means that the wave-length varies proportionally to the ratio of transformation.

Secondly, the impedance of the circuits connected to the tube is of great importance. This impedance is under the same conditions as mentioned above for the frequency, defined by the formula:

$$Z = \frac{1}{C_1 R}$$

and must be adapted to the impedance of the electron tube, in order to obtain a sufficient radiation and a good efficiency. If the conditions mentioned, namely that the transformer has no leakage nor losses and no distributed capacity and $C >> u^2 C_1$, are not exactly fulfilled, the principle of regulating the efficiency of the apparatus by altering the winding-ratio of the coupling coil or coils will not in the least be affected. Leakage of the transformer has the effect of increasing the resulting inductance (l in the formula for F_1), so that the inductance of the antenna coil (12, Figure 1) may be reduced or this coil omitted. By building suitable coils the losses in the transformer in general will be very small.

Particularly for short waves, where $u < 1$, the condition $C >> u^2 C_1$ will be as a rule fulfilled.

The deviations from the theoretical case will have no other effect than to make it dif-

ficult to calculate the correct winding-ratio in advance. On the other hand it is easy to determine experimentally the positions of the adjustable contacts or winding-ratio, which will give the wanted wave-length at a good efficiency even when the distributed capacity of the coil or transformer is not negligible.

When Z is smaller than the tube-impedance, the ratio A. C. output to D. C. input will be small and the efficiency of the tube will be bad.

R may be very great, more particularly with short waves, so that Z has a tendency to drop and thus detrimentally affect the operation of the discharge tube. The present method makes it possible to alter l in co-operation with the value of R and to adjust the wave-length with the aid of the ratio of transformation. When applying the present invention on the above lines, there is no difficulty in obtaining a good efficiency even in case very short waves are used, and also when the aerial, whatever its dimensions, is connected by direct coupling to the anode of the tube. As the aerial capacity does not appear in the formula for the wave-length the present method has moreover the advantage that the radiated wave-length can be easier kept constant. Usually an aerial, when emitting waves having a wave-length several time shorter than its natural wave length has a high total resistance R which varies only slightly with the different short wave-lengths used. Thus the ratio of the anode transformer (coil 6 in Figure 1) must be approximately proportional to the wave-length, in order to obtain the same good results on different wave-lengths.

In Figure 5 the aerial is connected directly to the grid circuit of the tube 1 with the aid of the coil 14. By suitably operating the contacts 15 and 16 or any other known regulating means, the higher or one of the higher resonant frequencies of the coupled circuits is tuned to, or in case of beat reception, approximately tuned to the wave-length to be received. The signals may be rendered audible in the anode circuit by suitable means. The method of tuning the system comprising the aerial circuit gives another advantage over the generally used method for reception of short waves, where the aerial circuit is not tuned.

An adjustable inductance 17 is inserted in the anode circuit in order to obtain the proper impedance in the said circuit for the wave-length which is to be received.

In the receiving circuits of Figures 5 and 6 the resulting capacity between grid and filament terminals corresponds to the capacity C_1 (mentioned above).

A receiving arrangement of the same kind is illustrated in Figure 6 for amplified reception in which the signals received are am-

plified by the tube 1 and forwarded to the grid of the following tube. In this case the higher or one of the higher resonant frequencies also of the intermediate circuits is regulated to the wave-length to be received. The capacity of one of the tightly coupled circuits may be large, which is also an advantage when receiving short waves.

All systems of connection used in this method may be carried out as push-pull connection if the aerial has only an inductive coupling with the tube. There is, however, a case in which a direct coupling of aerial and tube circuits is possible under use of push-pull connection. For that purpose (see Fig. 7) two vertical aerials 8 and 8a are located at a distance apart of half the wave-length wanted and are directly coupled to the tubes 1 and 1a. The middle of the anode coils 6, 6a is earthed, the distances between the lower ends of the aerials and the earth connection being equal. Anode current is supplied by a suitable source of current feeding each of the anodes through a high frequency choke coil.

The anodes of both tubes used are connected at equal distances from the earth connection, so that a diagram of connections is obtained composed of Figure 1 and its image. The currents in the two aerials will then have a phase difference of 180° , which results in a directional effect.

The invention is not limited to the use of connections in which the anode circuit and the grid circuit are coupled to each other only by means of the anode-grid capacity of the discharge tube. Any known means for coupling these circuits outside the tube may be used without departing from the invention.

What I claim is:—

1. The combination with a thermionic discharge tube having an input circuit and an output circuit, of a high frequency network constituted by a plurality of tightly coupled circuits connected in one of said tube circuits so as to form a network with a plurality of resonance frequencies lying in the range of radio frequencies and means for bringing one of the higher frequencies into action.

2. The combination with a thermionic discharge tube having an input circuit and an output circuit, of a high frequency network constituted by a plurality of tightly coupled circuits connected in one of said tube circuits so as to form a network with a plurality of resonance frequencies lying in the range of radio frequencies, and means in the other circuit for bringing one of the higher frequencies into action.

3. The combination with a thermionic discharge tube having an input circuit and an output circuit, of a high frequency network constituted by a plurality of tightly coupled circuits connected in the out-

put circuit so as to form a network with a plurality of resonance frequencies lying in the range of radio frequencies and means in the input circuit for causing the tube to oscillate to one of the higher frequencies.

5. The combination with a thermionic discharge tube having an input circuit and an output circuit, of a high frequency network constituted by a plurality of tightly coupled circuits connected in the output circuit and including an antenna, said network having a plurality of resonance frequencies lying in the range of radio frequencies, and means in the input circuit for causing the tube to oscillate at one of the higher of said frequencies.

6. The method of regulating the ratio of direct current input to alternating current output in a thermionic transmitter having its output circuit tightly coupled to the radiating circuit through a transformer to form a high frequency network with a plurality of resonance frequencies of radio frequency at one of which the thermionic transmitter oscillates, which comprises changing the winding ratio of the transformer while maintaining the resonant frequency of the coupled circuits and feed-back coupling constant.

7. The combination with a thermionic discharge tube having an input circuit and an output circuit, of a transformer, a plurality of circuits tightly coupled through said transformer and connected in one of said tube circuits forming a high frequency network resonant to a plurality of radio frequencies, and means for varying the winding ratio of said transformer while maintaining one of the frequencies to which said network is resonant substantially constant.

8. The combination with a thermionic tube, of an output circuit therefor comprising a high frequency network constituted by a plurality of tightly coupled circuits, so as to form a network with a plurality of resonance frequencies lying in the range of radio frequencies, and a control circuit therefor influenced by the output circuit to cause the tube to oscillate to one of said frequencies, said control circuit being adjusted to cause the tube to oscillate at one of the higher of said frequencies.

9. In combination, a thermionic discharge tube having an input and an output circuit, one of said circuits being tightly coupled to a third circuit by means of a common coil to form a high frequency network with a plurality of resonance frequencies of radio frequency at one of which the thermionic tube oscillates, and a control coil in the other tube circuit for determining the frequency to which the tube is to respond, said third circuit being resonant to a lower frequency than the said input circuit.

10. In testimony whereof I hereunto affix my signature.

65 GERRIT SCHOTEL.
